UNITED STATES PATENT OFFICE

2,486,856

ELECTRON LENS

Gerhard Liebmann, Cambridge, England, assignor to General Electric Company, a corporation of New York

Application October 14, 1948, Serial No. 54,381
In Great Britain April 12, 1947

10 Claims. (Cl. 250—160)

1

This invention relates to improvements in lenses of the magnetic type, such as are employed for focusing a beam of electrons.

Lenses employing magnetic or electric fields to focus beams of particles such as electrons have been used extensively in recent years. In particular, these lenses have found useful application in an instrument commonly known as an electron microscope, such as is described in an article entitled "Electron microscopy" appearing in the General Electric Review, December 1944.

The resolving power of the electron microscope is limited by the diffraction effect and by spherical and chromatic aberration in the electron lenses, particularly in the objective lens, even if space charge effects, asymmetries leading to astigmatism, and other defects of the electron optical system are avoided. The image of a point situated on the electron-optical axis is spread out into a disc of confusion, the radius of which, when referred back to the object space, is approximately given by

$$\delta T = k_1 (\delta_D^2 + \delta_S^2 + \delta_C^2)^{1/2} \quad (1)$$

where the errors due to the diffraction effects, δ_D , to spherical aberration, δ_S , and to chromatic aberration, δ_C , are given by

$$\delta_D = k_2 \lambda / \alpha \quad (2)$$

$$\delta_S = C_S \alpha^3 \quad (3)$$

and

$$\delta_C = \alpha [(C_{cv} \Delta V / V)^2 + (C_{ch} \Delta H / H)^2]^{1/2}$$

In these equations, α is the semi-angle of the imaging electron bundle, λ the electron wave length, V the accelerating voltage, ΔV the fluctuation of the accelerating voltage, H the magnetic field strength, and ΔH the fluctuation of the magnetic field strength.

The values of the constants k_1 and k_2 are at present not quite certain, values of between 0.5 and 1.0 being usually assumed. The spherical aberration constant C_S and the two chromatic aberration constants C_{cv} and C_{ch} have, in previously constructed instruments, values of 0.2 cm. to 2.0 cm. It has also recently been shown that the magnetic saturation of iron pole pieces forming the electron lenses leads to an optimum resolving power for an accelerating voltage of $V=50$ to 60 kv. ($\lambda \approx 5 \times 10^{-10}$ cm.), the resolving power of the best present instruments approaching 10^{-7} .

The present invention provides a means of correcting primary spherical aberration in a magnetic electron lens which comprises combining with said lens a diverging electrostatic electron lens that has a marginal focal length which is

2

smaller than the paraxial focal length. Such a lens can, for instance, be realized by applying an electrostatic field between a conducting plane or curved metal film, which is thin enough to be permeable to electrons, and a cylinder spaced a short distance away from the metal film and having its axis perpendicular to it, the electric field vector pointing from the metal film toward the cylinder.

10 A diverging lens of this kind has been found to have the required property of a marginal focal length which is shorter than the paraxial focal length f_0 . The relative difference f/f_0 of the marginal or zonal focal length of the described 15 diverging lens can be varied over a wider range by varying the diameter or distance of the said cylinder and by adjusting the potential difference between metal film and cylinder. It is possible to produce a considerable amount of longitudinal 20 zonal spherical aberration even in weak lenses, and the strong converging magnetic lens need not lose much of its refractive power by being combined with a correcting diverging electrostatic lens. As the same law governs primary aberration in weak and in strong lenses, and in positive 25 and negative lenses, it is possible to correct spherical aberration over the whole range governed only by primary spherical aberration. Thus, a lens can be corrected in the described way 30 up to semi-angles of $\alpha \approx 0.2$, whereas the uncorrected electron microscope objectives used hitherto can only accept rays of a semi-angle of less than 0.01 before spherical aberration limits the resolving power.

35 Other objects and advantages of the invention will appear from the following detailed description taken in conjunction with the accompanying drawing which is a diagrammatic cross section of an electron lens suitably embodying the invention.

40 The electron lens shown includes the combination of an electromagnetic lens and an electrostatic lens. The electromagnetic lens comprises an annular exciting coil 1 which is enclosed by an envelope 2, preferably of metallic material such as iron, that is provided in its bore with a spaced apart pair of pole pieces 3 and 4. The envelope 2 may be extended along its bore, as shown, to provide a means for making the 45 lens an integral part of an electron microscope. A spacer 5 of non-magnetic material such as brass is inserted within a gap in the bore of the envelope 2 between the pole pieces and may be suitably sealed therein to form a vacuum-tight 50 enclosure for the exciting coil. To provide exci-

tation for the exciting coil, leads 11 and 12 may be brought out through the envelope 2 in a suitable manner and connected to a source of direct current potential (not shown). The electrostatic lens comprises two electrodes, one of which includes a metal film 6 which may be mounted as shown on a supporting ring 7, secured to the pole piece 3 so that it extends across the bore through the pole piece. The other electrode is formed by pole piece 4 which may be insulated from the envelope 2 by a sleeve 8 and connected through an insulated lead 9 to a suitable source of direct current potential (not shown).

The thickness of the metal film 6 should be such that the image quality is not impaired by electrons being scattered to an appreciable extent, but should obviously be as great as is consistent with this requirement for reasons of mechanical strength and accuracy. Thus, for lower electron accelerating voltages, it may be necessary to employ very thin but conducting metal films produced by evaporating aluminum or beryllium onto a very thin plastic film. At voltages in excess of 100 kv., it should be possible to employ thin metal films stretched tightly over a suitable frame. Although the film is illustrated as being substantially planar, it is to be understood that it may be curved in a convenient manner, the only requirement being that the portion through which electrons pass be normal to the optical axis. Also, the film 6 may be constructed in the form of a grid to minimize scattering of the electron beam.

Although the insulation of the pole piece 4 from the envelope 2 introduces a second air gap into the magnetic circuit of the lens, the effect of this second air gap need not be appreciable if, as is practicable, the reluctance of the gap between pole piece 4 and the envelope 2 is made considerably lower than the reluctance of the gap between the two pole pieces 3 and 4.

The bores through the pole pieces 3 and 4 are generally cylindrical in cross section. However, it may be desirable for some applications to construct the pole pieces with slightly elliptical bores or to provide means for distorting the bores slightly from a cylindrical shape. Therefore, the term "cylinder-like" will be employed as descriptive of the shape of the pole piece bores, and it will be understood that this term includes a slight departure from a truly cylindrical shape.

The invention has been described in connection with an electron microscope lens system in order that practical adaptations of the features of the invention may be adequately illustrated. It is obvious, however, that the above-described features can be applied to lenses other than electron microscope objective and projector lenses; for example, to lenses in high voltage or cathode ray tubes or lenses in fine X-ray tubes and the like.

Having described the principle of this invention and the best mode in which I have contemplated applying that principle, I wish it to be understood that the apparatus described is illustrative only, and that other means can be employed without departing from the true scope of the invention expressed in the following claims.

What I claim as new and desire to secure by Letters Patent of the United States is:

1. An electron lens comprising a spaced apart pair of pole pieces having cylinder-like bores coaxially aligned, a winding about both said pole pieces, means for exciting said winding to provide a magnetic flux linking said pole pieces to

form a magnetic lens, a conductive electron permeable member extending normal to the axis of said pole pieces within the space separating the adjacent ends of said pole pieces, and connecting means for establishing a potential difference between said member and at least one of said pole pieces to provide an electrostatic diverging lens having a marginal focal length smaller than its paraxial focal length.

2. An electron lens comprising a spaced apart pair of pole pieces having cylinder-like bores coaxially aligned, a winding about both said pole pieces, means for exciting said winding to provide a magnetic flux linking said pole pieces to form a magnetic lens, an electron permeable member extending across the bore of one of said pole pieces at the end nearest the other of said pole pieces, and connecting means for establishing a potential difference between said member and said other pole piece to provide an electrostatic diverging lens having a marginal focal length smaller than its paraxial focal length.

3. An electron lens comprising a first hollow cylinder-like pole piece, a second hollow cylinder-like pole piece coaxial with and spaced from said first pole piece, an annular winding about both said pole pieces, means for exciting said winding to provide a magnetic flux linking said pole pieces whereby a magnetic lens is produced, a thin electron permeable member supported by said first pole piece within the space separating the adjacent ends of said pole pieces, and connecting means for establishing a potential difference between said member and said second pole piece to provide an electrostatic diverging lens having a marginal focal length smaller than its paraxial focal length.

4. An electron lens comprising a spaced apart pair of pole pieces having cylinder-like bores coaxially aligned, a winding about both said pole pieces, means for exciting said winding to provide a magnetic flux linking said pole pieces to form a magnetic lens, a thin electron permeable member conductively attached to one of said pole pieces at the end nearest the other of said pole pieces, and connecting means for establishing a potential difference between said member and said other pole piece to provide an electrostatic diverging lens having a marginal focal length smaller than its paraxial focal length.

5. An electron lens comprising a spaced apart pair of pole pieces having cylinder-like bores coaxially aligned, a winding about both said pole pieces, means for exciting said winding to provide a magnetic flux linking said pole pieces to form a magnetic lens, a thin electron permeable member conductively attached to and extending across the bore of one of said pole pieces at the end nearest the other of said pole pieces, and connecting means for establishing a potential difference between said member and said other pole piece to provide an electrostatic diverging lens having a marginal focal length smaller than its paraxial focal length.

6. An electron lens comprising a spaced apart pair of pole pieces having cylinder-like bores coaxially aligned; an annular winding enclosed by a metallic envelope disposed about both said pole pieces, one of said pole pieces being insulated from said envelope; means for exciting said winding to provide a magnetic flux linking said pole pieces to form a magnetic lens; an electron permeable member conductively attached to the non-insulated pole piece at the end nearest the insulated pole piece, and insulated means for

connecting a source of potential to said insulated pole piece to provide a potential difference between said member and said insulated pole piece to form an electrostatic diverging lens having a marginal focal length smaller than its paraxial focal length.

7. An electron lens comprising a spaced apart pair of pole pieces having cylinder-like bores coaxially aligned; an annular winding enclosed by an envelope disposed about both said pole pieces, said envelope having an annular non-magnetic portion in its bore coextensive with the space between the adjacent ends of said pole pieces; means for exciting said winding to provide a magnetic flux linking said pole pieces to form a magnetic lens; an electron permeable member extending normal to the axis of said pole piece bores and within the space separating the adjacent ends of said pole pieces, and connecting means for establishing a potential difference between said member and said other pole piece to provide an electrostatic diverging lens having a marginal focal length smaller than its paraxial focal length.

8. An electron lens comprising a spaced apart pair of pole pieces having cylinder-like bores coaxially aligned; an annular winding enclosed by a metallic envelope disposed about both said pole pieces, said envelope being insulated from one of said pole pieces and having an annular non-magnetic portion in its bore coextensive with the space between the adjacent ends of said pole pieces; means for exciting said winding to provide a magnetic flux linking said pole pieces to form a magnetic lens; an electron permeable member conductively attached to the non-insulated pole piece at the end adjacent the insulated pole piece, and insulated means for connecting a source of potential to said insulated pole piece to provide a potential difference between said member and said insulated pole piece to form an electrostatic diverging lens having a

marginal focal length smaller than its paraxial focal length.

9. An electron lens comprising a spaced apart pair of pole pieces having cylinder-like bores coaxially aligned and tapered adjacent end portions; a winding enclosed by a metallic envelope disposed about both said pole pieces, said envelope being insulated from one of said pole pieces and having an annular non-magnetic portion in its bore coextensive with the space between said pole pieces defined by the adjacent non-tapered portions thereof; means for exciting said winding to provide a magnetic flux linking said pole pieces to form a magnetic lens; an electron permeable member conductively attached to the non-insulated pole piece at the end adjacent the insulated pole piece, and insulated means for connecting source of potential to said insulated pole piece to provide a potential difference between said member and said insulated pole piece to form an electrostatic diverging lens having a marginal focal length smaller than its paraxial focal length.

10. An electric lens comprising a spaced apart pair of pole pieces having cylinder-like bores coaxially aligned; a winding enclosed by a metallic envelope disposed about both said pole pieces, said envelope being insulated from at least one of said pole pieces; means for exciting said winding to provide a magnetic flux linking said pole pieces to form a magnetic lens; an electron permeable member extending normal to the axis of said pole piece bores and within the space separating the adjacent ends of said pole pieces, and insulated means for connecting a source of direct current between said member and at least one of said pole pieces to provide an electrostatic diverging lens having a marginal focal length.

Certificate of Correction

Patent No. 2,486,856

November 1, 1949

GERHARD LIEBMANN

It is hereby certified that errors appear in the printed specification of the above numbered patent requiring correction as follows:

Column 1, line 50, for "10⁻⁷." read 10⁻⁷ cm.; column 2, line 1, for "paranial" read *paraxial*; column 4, line 14, for "manetic" read *magnetic*;
and that the said Letters Patent should be read with these corrections therein that the same may conform to the record of the case in the Patent Office.

Signed and sealed this 25th day of April, A. D. 1950.

[SEAL]
